UNITED STATES PATENT OFFICE

EDWIN HENRICSON, OF DETROIT, MICHIGAN

JIG

Application filed October 21, 1926. Serial No. 143,052.

My invention aims to provide a jig that may be advantageously used for holding various kinds of work to be drilled, bored or otherwise operated, the jig being designed so that material may be removed from the same to adapt the jig for other work than that for which it is specially designed.

My invention further aims to provide a jig with a substantially guided jaw and novel means for raising and lowering the jaw relative to a stationary bushing support. The adjusting means, under normal conditions ensures a positive and reliable clamp for a piece of work, but there are times when irregularities or inequalities of pieces of work necessitate a better clamping action. For this purpose the jaw adjusting mechanism includes an auxiliary take-up device by which the throw or adjustment of the jig jaw may be regulated.

These improvements will be hereinafter specifically described and then claimed, and reference will now be had to the drawings, wherein

Figure 1 is a side elevation of the jig, partly broken away and partly in section;

Fig. 2 is a front elevation of the jig, partly in section; and

Fig. 3 is a horizontal sectional view of the jig.

Reference will be had to Figs. 1 to 3 inclusive showing a jig as comprising a base 1 having a standard 2 and detachably mounted on the upper end of the standard, by screw bolts 3 or other fastening means, is an overhanging bushing support 4 which projects from the front side of the standard 1. The upper end of the standard has a surplus amount of material 5 which may be trimmed off or otherwise removed so as to place the support 4 in a lowered position from that shown in Fig. 1.

The base 1, under the support 4, has bored bearings 6 and snugly fitted in these bearings are parallel posts 7 having the lower ends thereof flush with the lower face of the base 1 and provided with sockets 8, so that a tool may be mounted in said sockets to facilitate removal of said posts. These posts extend upwardly from the base 1

parallel to the front face of the standard 2 to serve as guides for a jaw 9 that confronts the support 4 and cooperates therewith for gripping a piece of work. The jaw 9 has tubular end portions 10 to receive the posts 7 and the tubular end portions 10 bear against the front face of the standard 2 and thus cooperate with the jaw 9 in sliding against the standard to press the jaw in its movement relative to the post 7. Connecting the tubular portions 10 of the jaw 9 is a web 11 spaced from the front face of the standard 2 so as to provide a link chamber or recess 12.

Centrally of the standard 2 is a transverse opening 13 communicating with a bearing 14 to permit of a rock shaft 15 being journaled in the bearing and standard. Suitably fixed on the outer end of the rock shaft 15 is a crank or lever 16 normally horizontal, as shown in Fig. 2 and adapted to be swung from the position shown in Fig. 2 upwardly to a reverse position, at the opposite side of the jig. One position of the crank or lever 16 is for an open condition of the jaw 9 relative to the support 4 and the opposite position of the crank or lever represents a closed position of the jaw 9.

On the inner end of the rock shaft 15 is a concentric head 17 provided with an eccentrically disposed pin 18 journaled in the upper end of a link 19 slidable between the head 17 and the web 11 of the jaw structure. On the lower end of the link 19 is a pin 20 journaled in an eccentrically disposed socket 21 of a rotatable bearing 22 journaled in the lower portion of the web 11. The bearing 22 may be rotated and fixed relative to the web 11 by a jam nut 23 and this nut and its bearing constitutes an auxiliary take-up connection between the link 19 and the slidable jaw structure.

There may be irregularities or inequalities in the pieces of work to be held in the jig. If so, the auxiliary take-up device may be quickly adjusted so that there will be a positive and reliable clamping action of the jaw 9 for holding a piece of work under the support 4. However, there may be pieces of work that could not be firmly held by the

limited action of the adjustable jaw, therefore this jaw has a surplus of material 24 which can be removed when the jig is to be adapted for work other than that for which it is originally designed. As shown a piece of work within certain limits can be firmly held. If a larger piece of work is to be held material may be removed from the gripping face of the jaw 9. If a smaller piece of work is to be held material may be removed from the upper end of the standard 2. So with this surplus material embodied in the jig it is possible to convert the jig into a holding device for work of different dimensions than that for which it is originally designed.

It is thought that the utility of my invention will be apparent without further description, and while in the drawing there is illustrated a preferred embodiment of the jig and its bushing and guide, it is to be understood that the structural elements are susceptible to such variations and modifications as fall within the scope of the appended claims.

What I claim is:—

1. A jig comprising a base, a standard on said base, an overhanging support mounted on the upper end of said standard, posts carried by said base, a jaw slidable on said posts against said standard, a rock shaft journaled in said standard, a bearing mounted transversely in said jaw for rotative adjustment therein and having an eccentric socket, and a link connection between said shaft and socket.
2. A jig comprising a base, a standard on said base, an overhanging support mounted on the upper end of said standard, posts carried by said base, a jaw slidable on said posts against said standard, a rock shaft journaled in said standard, a link connection between said rock shaft and said jaw so that rocking of said shaft adjusts said jaw, and an eccentric take-up device between said link and jaw by which said jaw may be adjusted relative to said link.
3. A jig comprising a base, a standard on said base, an overhanging support mounted on the upper end of said standard, posts carried by said base, a jaw slidable on said posts against said standard, a rock shaft journaled in said standard, a bearing mounted transversely in said jaw for rotative adjustment therein and having an eccentric socket and an exposed portion adapted for engagement by a wrench, a link extending from said rock shaft to said bearing member, and a pin extending from said link into said socket.

60 In testimony whereof I affix my signature.
EDWIN HENRICSON.
